SECTION FOR STOVES OR THE LIKE

Filed May 3, 1926

FIG. 1.

FIG. 2.

GUSTAF ALBERT ARONSON
INVENTOR

By *O. H. Aronson*
his ATTY.

UNITED STATES PATENT OFFICE.

GUSTAF ALBERT ARONSON, OF STOCKHOLM, SWEDEN.

SECTION FOR STOVES OR THE LIKE.

Application filed May 3, 1926, Serial No. 106,250, and in Sweden January 26, 1925.

This invention relates to a section for stoves or the like, which section consists of a number of approximately vertical bars of potstone, chamotte or other suitable material, which bars have a round or essentially round cross section and which suitably are joined to each other by means of an adhesive also serving as stopping between the bars.

10 A stove section made according to this invention offers the advantage of the inner heat absorbing surface as well as the outer heat radiating surface of the section becoming considerably larger than the corresponding surfaces of usual stove sections of the same size. From the manufacturing point of view the section offers the advantage, that it may be made at a low cost and, in consequence of its form, with the greatest 20 possible saving of material.

A stove section according to this invention is shown in the accompanying drawing; Fig. 1 is a vertical and Fig. 2 a horizontal section of the stove section.

25 The stove section consists of a number of approximately vertical bars 1 having round cross sectional form and being made of potstone, chamotte or another suitable material. Each bar is provided with a longitudinal

groove 2 engaged by the adjacent bar. In 30 the groove 2 is placed an adhesive 3 between the two bars, said adhesive serving as a stoppage between the bars. The different sections are built together in a suitable way for example by means of frames (or parts 35 of frames) 4 which are mounted on the upper and the lower side of each section and which may be so arranged, that the frame on the lower side of a section engages or embraces the frame on the upper side of 40 the adjacent section, or vice versa.

Having now described my invention, what I claim as new and desire to secure by Letters Patent is:

1. A ceramic heating furnace formed of 45 individual superimposed sections, each thereof comprising vertical juxtaposed substantially round bars of ceramic material, and a binding medium for uniting one bar to another.

2. A heating furnace, as claimed in claim 1, in which each of said bars of ceramic material is recessed longitudinally thereof for the reception of said binding medium, and which recess the adjacent bar engages.

In witness whereof, I have hereunto signed my name.

GUSTAF ALBERT ARONSON.
